(57) **CLAIM**

The ornamental design for a welding machine, as shown and described.

DESCRIPTION

FIG. 1 is a top, front, left side perspective view of a welding machine showing our new design;

FIG. 2 is a top, rear, right side perspective view thereof;

FIG. 3 is an enlarged front elevation view thereof;

FIG. 4 is an enlarged rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" (identified in FIG. 1), shown at a greater scale for clarity of disclosure;

FIG. 10 is an enlarged view of detail "10" (identified in FIG. 2), shown at a greater scale for clarity of disclosure; and,

FIG. 11 is an enlarged view of detail "11" (identified in FIG. 2), shown at a greater scale for clarity of disclosure.

The broken lines shown in the drawings depict portions of the welding machine that form no part of the claimed design. The dot-dash broken lines in FIGS. 1, 2, 9, 10 and 11 depict the boundaries of the enlargements that form no part of the claimed design. None of the elements shown in broken lines form a part of the claimed design.
